UNITED STATES PATENT OFFICE.

WILLIAM H. O'CONNOR, OF NEWARK, NEW JERSEY.

LUBRICATING DEVICE.

No. 832,875.

Specification of Letters Patent.

Patented Oct. 9, 1906.

Application filed November 14, 1905. Serial No. 287,230.

To all whom it may concern:

Be it known that I, WILLIAM H. O'CONNOR, a citizen of the United States, residing at Newark, in the county of Essex and State 5 of New Jersey, have invented certain new and useful Improvements in Oiling or Lubricating Devices; and I do hereby declare the following to be a full, clear, and exact description of the invention, such as will enable others 10 skilled in the art to which it appertains to make and use the same, reference being had to the accompanying drawings, and to figures of reference marked thereon, which form a part of this specification.

15 The objects of this invention are to secure a uniform pressure of oil or other lubricating fluid, whereby the fluid will be fed uniformly to the wearing parts of the machine; to thus secure a more regular and constant supply of 20 lubricant at the bearings of said parts; to enable the lubricant to be fed from the receptacle therefor until the same is practically exhausted without any necessity of premature replenishing; to reduce the labor of replenishing the oil cups or receptacles; to facilitate 25 the work of replenishing the lubricant; to economize the use of oil because of the more constant and regular normal supply of a minimum quantity, and to secure other advantages and results, some of which may be referred to hereinafter in connection with the 30 description of the working parts.

The invention consists in the improved lubricating device and in the arrangements 35 and combinations and parts of the same, all substantially as will be hereinafter set forth, and finally embraced in the claim.

Referring to the accompanying drawings, in which like numerals of reference indicate 40 corresponding parts in each of the figures, Figure 1 is a central vertical section of the improved lubricating device, and Fig. 2 is a plan of the lower end of the lubricant-reservoir.

In said drawings, 5 indicates the body of 45 the lubricant-receptacle, which is preferably of glass and is closed at the top to form a chamber 51, in which a partial vacuum may be formed above the supply of lubricant. Below the body 5 the receptacle is reduced 50 and made cylindrical, as at 6, to fit more or less closely into the metallic cup hereinafter referred to, and below the cylindrical part 6 the said receptacle is further reduced, as at 7, preferably on inwardly-curved lines, as shown, 55 the reduced parts being hollow to form a pas-

sage 8 for the downflowing lubricant. The cylindrical part 6 is not so close in its relation to the inner wall of the cup as to prevent an air-passage therebetween. Indeed, I prefer to form in the outer side wall of said cylindrical portion a groove or passage 9 for venting the annular chamber 10, formed around the smallest part 7 of the neck. The oil-cup 11 is preferably of metal, such as brass, and is of greater depth than the length of the neck 60 65 is provided with a valved feed extension 12, of which 13 indicates the spigot, adapted to be turned by a finger piece or portion 14, the said spigot governing the flow of lubricant through the exit-passage 16 to the parts to be 70 lubricated.

The device may be attached to the machinery to be lubricated by the threaded nipple 15 or by any of the means common in the art, and the valve 13 or other means for governing 75 the flow from the cup 11 may be varied as may be found best.

In operating the device the lubricant is filled into the body 5, the open neck being turned up to receive the liquid. The cup 11 80 is then placed over the neck and the whole inverted to the position shown in Fig. 1, so that a portion of the liquid flows down into said cup, a partial vacuum being formed in the upper part of the body portion. This 85 vacuum serves to prevent a further downflow from the large storage-chamber in the body, excepting as air is permitted to flow up through the neck-passage 8 as the liquid in the chamber 17 of the cup is fed down 90 from said chamber 17 through the passage 16 to the parts to be lubricated. The air-passage 9 and annular chamber 10, being 95 open to normal air-pressure, permit a free gravitation of the liquid in the oil-cup, and as this column of liquid remains constant until the supply of oil is nearly exhausted, being fed from above as air is permitted to enter under the edge of part 7, the pressure 100 is uniform and but of a small degree, so that the oil is not at first flushed upon the bearings and afterward fed in lessening quantities, but is fed regularly, as above indicated.

Having thus described the invention, what I claim as new is—

An improved oiling device, comprising a reservoir closed at its top and having a reduced lower end with an exit-passage for the lubricant, said reservoir having a reduced cylindrical lower part and an inwardly-turned 110

lower extremity adapted in conjunction with the cup to form an annular chamber around about said extremity, and a valved cup adapted to receive said cylindrical part at 5 its upper end and form a chamber at its lower part for a limited supply of lubricant, provision being made for introduction of atmospheric pressure into the cup.

In testimony that I claim the foregoing I have hereunto set my hand this 7th day of 10 November, 1905.

WILLIAM H. O'CONNOR.
